[57] CLAIM

The ornamental design for a combined camper jack and bracket, as shown and described.

DESCRIPTION

FIG. 1 is a front, side and end perspective view of the combined camper jack and bracket;

FIG. 2 is a top plan view of the combined camper jack and bracket;

FIG. 3 is a bottom plan view of the combined camper jack and bracket;

FIG. 4 is a right side elevational view of the combined camper jack and bracket;

FIG. 5 is a front elevational view of the combined camper jack and bracket;

FIG. 6 is a left side elevational view of the combined camper jack and bracket; and,

FIG. 7 is a rear elevational view of the combined camper jack and bracket.

The broken lines portion of the illustration of a camper body in FIGS. 1 through 3 are for illustrative purposes only and forms no part of the claimed design for the combined camper jack and bracket.
